Primary Examiner — Lakiya G Rogers*Assistant Examiner* — Harold E Blackwell, II(74) *Attorney, Agent, or Firm* — Alston & Bird LLP(57) **CLAIM**

The ornamental design for an LED lamp, as shown and described.

DESCRIPTION

FIG. 1 is a perspective view of an LED lamp according to an exemplary embodiment of the present design;

FIG. 2 is a front view of the LED lamp shown in FIG. 1; FIG. 3 is a top view of the LED lamp shown in FIG. 1; and, FIG. 4 is a bottom view of the LED lamp shown in FIG. 1. The broken lines in the drawings illustrate portions of the light emitting diode lamp, which form no part of the claimed design.
